DAVID W. STORER, OF BANGOR, MAINE.

Design No. 3,254, dated November 17, 1868.

DESIGN FOR A TRADE-MARK

The Schedule referred to in these Letters Patent and making part of the same.

To all persons to whom these presents may come:

Be it known that I, DAVID W. STORER, of Bangor, of the county of Penobscot, and State of Maine, have invented or produced a new Design for a Trade-Mark; and do hereby declare the same to be fully described in the following specification, and represented in the accompanying drawing.

In such drawing, A denotes a pen-wiper, composed of a woollen ball, a, and a glass base or stand, b. Below this is a key, B, and over the ball a, and arranged saltier-wise, are two pens, C C, the whole constituting the design in question.

I claim the said design as my invention or production.

DAVID W. STORER.
